J. J. JONES.
JOINT FOR LOCOMOTIVE EXHAUST PIPES.
APPLICATION FILED APR. 2, 1913.

1,076,289.

Patented Oct. 21, 1913.

FIG.1

FIG.2

UNITED STATES PATENT OFFICE.

JOSHUA J. JONES, OF SCHENECTADY, NEW YORK.

JOINT FOR LOCOMOTIVE EXHAUST-PIPES.

1,076,289.

Specification of Letters Patent.

Patented Oct. 21, 1913.

Application filed April 2, 1913. Serial No. 758,431.

To all whom it may concern:

Be it known that I, JOSHUA J. JONES, of Schenectady, in the county of Schenectady and State of New York, have invented a 5 certain new and useful Improvement in Joints for Locomotive Exhaust-Pipes, of which improvement the following is a specification.

My invention is more particularly designed for application in connection with the exhaust pipes of locomotives of the articulated or "mallet" type, in which the forward (ordinarily low pressure) cylinders are carried upon a truck frame which is 15 adapted to swivel relatively to the boiler, and in which, consequently, it becomes necessary to make an articulated joint between the section of the exhaust pipe which is supported upon the truck and the upper section 20 thereof, which is located, in the usual manner, in the smoke box of the boiler.

The object of my invention is to provide means whereby the insertion of packing in the stuffing box of the joint may be readily 25 and conveniently effected, and the insertion of the packing may be made when the locomotive is assembled and in readiness for the installation of the exhaust pipe and nozzle in the smoke box, under which conditions it is extremely difficult to insert the packing from beneath the smoke box, as has been the practice heretofore.

The improvement claimed is hereinafter fully set forth.

35 In the accompanying drawings: Figure 1 is a vertical longitudinal central section through the smoke box of an articulated locomotive, illustrating an embodiment of my invention; and, Fig. 2, a horizontal section, on the line *a a* of Fig. 1.

40 My invention is herein exemplified as applied in the means for connecting the lower section, 1, of the exhaust pipe of an articulated or "mallet" locomotive, which, as above stated, is supported upon the truck, and the upper section, 1^a, which is located in the inside of the smoke box, 2, of the boiler, and to the upper end of which the exhaust nozzle, 1^b, is attached. In the practice of my invention, I provide a cylindrical thimble casing, 3, the bore of which 45 extends continuously from one of its ends to the other, so that it is open throughout its entire internal diameter at each end. A 50 circumferential flange, 3^b, is formed on the

lower end of the thimble casing, through which flange it is secured by bolts, 3^a, to the inside of the smoke box, 2, at the bottom thereof, and preferably in line axially with the stack, 2^a. A similar flange, 3^c, is formed 60 on the upper end of the thimble casing, for the attachment thereto of the upper section, 1^a, of the exhaust pipe, the lower flange, 1^d, of which, alone constitutes the top closure of the bore of the thimble casing. The rear 65 end of the lower section, 1, of the exhaust pipe, is upwardly curved, and its upper end is formed into a ball or section of a sphere, 1^e, of smaller diameter than the bore of the thimble casing, the center of which ball is 70 in line axially with the casing, and which is pivotally suspended therein by a supporting ball flange ring or socket, 4, bored out to fit the ball, 1^e, and secured to the bottom flange, 3^b, of the thimble casing, by studs, 4^a, a 75 spacing gasket, 4^b, being interposed between the flange, 3^b, and the ring, 4.

A centering ring, 5, spherically bored in conformity with the surface of the ball, 1^e, is fitted between the upper portion of said ball and the thimble casing, 3, the top 80 of the centering ring fitting against the flange, 1^d, on the bottom of the upper exhaust pipe section, 1^a, which is secured to the upper flange, 3^c, of the thimble casing, by 85 studs, 6, passing through said flange and through the flange, 1^d. A packing adjusting ring, 7, is fitted between the ball, 1^e, and thimble casing, 3, on the top of the flange ring or socket, 4, and is vertically adjustable by screws, 7^a, engaging the ring, 4, and accessible from the lower side of said ring, to effect compression, as desired, of a body of suitable packing, 8, which is interposed in the annular space between the rings, 5 and 90 7, and between the ball, 1^e, and thimble casing, 3. The thimble casing, 3, and ring, 4, constitute a stuffing box, by means of which a steam tight swiveling joint between the lower and upper sections of the exhaust 95 pipe is effectively maintained.

By reason of the difficulty of access, from beneath the smoke box, to any form of stuffing box applied at the connection of the exhaust pipe sections, due to the presence of adjacent machine elements, the insertion of the packing from the inside of the smoke box, after the locomotive has been assembled and before finally securing in place the exhaust pipe and other smoke box fixtures, 110

is very desirable, and such insertion is readily effected in the use of my invention. After ascertaining that the spacing gasket, 4^b, is of proper thickness to insure easy and close fitting joints between the ball, 1^c, and the rings, 4 and 5, the flange ring, 4, is lowered a short distance, by loosening the studs, 4^a, and the packing adjusting ring is also placed in its lowest position against the flange ring. After removing the upper exhaust pipe section and the centering ring, 5, the packing, 8, is properly fitted in from above; the ring, 5, is then replaced and the upper exhaust pipe section, 1^a, securely bolted to the thimble casing, after which the flange ring, 4, is fastened to the thimble casing, and the screws, 7^a, adjusted, if necessary, to impart the requisite tightness to the joint.

20 While my invention is herein set forth as applied in connection with an exhaust pipe through which steam is discharged from the low pressure cylinders of an articulated compound locomotive, it will be obvious to those familiar with locomotive construction that it may, without change of structural or operative principle, be similarly applied in connection with a receiver pipe through which steam is carried from the high pressure to the low pressure cylinders, the difference being merely in the location of the joint in an intermediate smoke box in the latter case, instead of in the ordinary smoke box at the front of the boiler, as in the instance illustrated.

I claim as my invention and desire to secure by Letters Patent:

1. The combination of a cylindrical thimble casing, which is open throughout the diameter of its bore at each end, and is adapted to be secured at its bottom to the inside of a locomotive smoke box, a lower exhaust pipe section fitting in said casing, with the provision of surrounding space for the reception of packing, and an upper exhaust pipe section secured detachably to, and constituting the entire upper closure of, the top of said casing.

2. The combination of a cylindrical thimble casing, entirely open at each end, and adapted to be secured at its bottom to the inside of a locomotive smoke box, a lower exhaust pipe section fitting in said casing, with the provision of surrounding space for the reception of packing, an upper exhaust pipe section secured detachably to the top of said casing, and a supporting ring, fitting in said casing, around the lower exhaust pipe section, and secured detachably to the bottom of said casing.

3. The combination of a cylindrical thimble casing, entirely open at each end, and having a bottom flange for attachment to the inside of a locomotive smoke box, and a top flange for attachment to an exhaust

pipe section, an upper exhaust pipe section secured detachably to said top flange, a lower exhaust pipe section fitting in the casing, with the provision of surrounding space for the reception of packing, a supporting ring fitting in the casing around said lower exhaust pipe section, and a spacing gasket interposed between said ring and the bottom flange of the thimble casing.

4. The combination of a cylindrical thimble casing entirely open at each end, and adapted to be secured at its bottom to the inside of a locomotive smoke box, a lower exhaust pipe section fitting in said casing, with the provision of surrounding space for the reception of packing, an upper exhaust pipe section secured detachably to the top of said casing, a supporting ring fitting in said casing, around the lower exhaust pipe section, and secured detachably to the bottom of the casing, and a packing adjusting ring surrounding the lower exhaust pipe section above the supporting ring.

5. The combination of a cylindrical thimble casing, entirely open at each end, and adapted to be secured at its bottom to the inside of a locomotive smoke box, a lower exhaust pipe section fitting in said casing, with the provision of surrounding space for the reception of packing, an upper exhaust pipe section secured detachably to the top of said casing, a supporting ring fitting in said casing, around the lower exhaust pipe section, and secured detachably to the bottom of the casing, a packing adjusting ring surrounding the lower exhaust pipe section above the supporting ring, and adjusting screws engaging the supporting ring and bearing on the packing adjusting ring.

6. The combination of a cylindrical thimble casing entirely open at each end, and adapted to be secured at its bottom to the inside of a locomotive smoke box, an upper exhaust pipe section secured detachably to the top of said casing, a lower exhaust pipe section having a ball on its upper end fitting in said casing, with the provision of surrounding space for the reception of packing, a spherically bored centering ring fitting the casing and the periphery of the ball and abutting the bottom of the upper exhaust pipe section, and a similarly bored supporting ring fitting around the ball, below its center, and secured detachably to the bottom of the casing.

7. The combination of a cylindrical thimble casing, entirely open at each end, and adapted to be secured at its bottom to the inside of a locomotive smoke box, an upper exhaust pipe section secured detachably to the top of said casing, a lower exhaust pipe section having a ball on its upper end fitting in said casing, with the provision of surrounding space for the reception of packing, a spherically bored centering ring fit-

ting the casing and the periphery of the ball and abutting the bottom of the upper exhaust pipe section, a similarly bored supporting ring fitting around the ball, below its center, and secured detachably to the bottom of the casing, a packing adjusting ring surrounding the ball above the sup-

porting ring, and adjusting screws engaging the supporting ring and bearing on the packing adjusting ring.

JOSHUA J. JONES.
